UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END CONSTRUCTION.

1,224,831.

Specification of Letters Patent.

Patented May 1, 1917.

Application filed March 16, 1915. Serial No. 14,696.

To all whom it may concern:

Be it known that I, PAUL M. BEARD, a citizen of the United States, residing at the city of St. Louis, State of Missouri, have 5 invented a certain new and useful Improvement in Car End Construction, of which the following is a full, clear, and exact description, such as will enable others skilled in the art to which it appertains to make and use 10 the same, reference being had to the accompanying drawings, forming part of this specification.

This invention relates generally to railway car construction, and specifically to certain improvements in car end structures. The characteristic feature of the invention is the formation of certain of the wall portions, notably the end plates and side plates adjacent the end plates, in such fashion that 20 they coöperate to form beam members which perform in the structure, functions of certain of the framing members now commonly employed.

The principal object of my invention is 25 to provide a construction which will give the car superstructure increased strength at its end portions.

Another object of my invention is to provide a form of construction for the end and 30 corner portions of cars which may be manufactured cheaply, and which will admit of repairs being made therein at small expense.

A further object of my invention is to so form certain of the side plates and the end 35 plates that they will coöperate to form corner posts.

A further object of my invention is to so form certain of the side plates and end plates that they will coöperate to form transverse framing members which will coöperate 40 to reinforce the end plates and brace the corner posts in proper position.

Other and further objects will be pointed out hereinafter, or will be obvious upon an 45 understanding of the construction.

It has become common practice to form certain of the side plates and end plates of railway cars of sheet metal, variously formed and secured together to provide the 50 car walls. Likewise, it has become good practice to replace damaged ends of box cars with ends formed of plates of sheet metal, which are attached at their outer

margins to the corner posts and upper and lower framing members of the car superstructure. One of the particulars in which such end structures have most frequently failed are the connections of the end plates to the car superstructure. It frequently occurs, when the metal ends are connected to 55 the wooden corner posts, or even to the framing members such as the transom posts, that they have been torn loose from their connections, by violent thrust of the car lading against their inner faces. The corner posts and transom posts are frequently 60 broken or splintered, with the result that the entire superstructure of the car is weakened, and the car rendered unfit for service.

In the accompanying drawings, I have 70 illustrated one form of my invention which is designed to obviate these and various other insufficiencies of the present structures,

Figure 1 being a front elevational view of 75 a car end forming a portion of one form of my invention;

Fig. 2 a cross section on line 2—2 of Fig. 1;

Fig. 3 a side view;

Fig. 4 a detail, being a vertical section on 80 line 4—4 of Fig. 1;

Fig. 5 an enlarged detail taken from Fig. 2;

Fig. 6 a detail illustrating a vertical section of a modified form;

Fig. 7 a side detail view illustrating the connection between the wall sheets and underframe members;

Fig. 8 a horizontal sectional detail through the corner and through a transom 90 or side post;

Fig. 9 is a front elevation detail illustrating the construction at the upper extremity of the corner post;

Fig. 10, another front elevation detail 95 illustrating the construction at the lower extremity of the corner post;

Fig. 11, a plan detail illustrating the top connection between the end and side sheets.

The form illustrated in the drawing includes a first section 1 and a second section 2 of suitable sheet metal having their vertical margin 4 turned rearwardly to 100 form corners. Adjacent their meeting edges, the sections have portions displaced outwardly to form offset portions 5 lying ob-

liquely to the plane of the sections. The margins are deflected from the planes of the offset portions 5 to provide the connecting flanges 6. The displaced portions 5 are widest at the center line of the sections and gradually narrow to the side margins, at which points the flanges 6 spring directly from the plane of the sections. When the sections are juxtaposed and their meeting edges secured together by fastenings seated in the flanges 6, the displaced portions 5 unite to form a transversely disposed bead or corrugation which is broadest and deepest at the center line of the 15 panels and gradually tapers in both depth and width toward the side margins. The connecting flanges 6 are carried around the corners. A tie plate 7 may be disposed across the inner side of this bead, and riveted to the sections along the sides of the 20 bead.

The numeral 8 represents side sheets forming portions of the car walls and secured at their upper and lower edges to 25 longitudinal framing members of the car and secured along vertical lines to any proper vertical framing members, such as the transom posts. At their terminal ends adjacent the corners of the car, these side 30 sheets 8 have their vertical margins shaped with a series of bends to form inset portions 9 and attaching flanges 10. These inset portions form vertically extending channels adjacent the terminal edges of the 35 sheets 8, which channels are located at the corners of the car in the position normally occupied by the corner posts. The vertical margins 4 of the end sheets overlap these channels at their reentrant sides, and 40 co-operate therewith to form vertical tubular members at the corners of the car, the side sheets and end sheets being secured together by vertical lines of fastenings 11 seated in the marginal portions thereof on both sides 45 of the inset portion 9.

In Figs. 7 to 11 inclusive is illustrated the manner in which the parts are connected to the car framing. As is illustrated in Fig. 7, which is a detail showing a side 50 view at the lower edge of the corner, it will be seen that the end sheet 2 extends down behind the end sill 12 and is secured thereto by the rivets 12^a, the lower edge of the sheet 2 being flanged horizontally. The 55 lower margin of the side sheet 8 extends down to lap the side sill 14, and is secured thereto by a line of fastenings 14^a. At the top the side sheet 8 is riveted to the side plate 15 which is the form of a Z bar or 60 other suitable flanged member, and a stay cap 16 which is shaped to conform to the corner, is applied to the top of the tubular corner post, and is riveted to the upper horizontal flange of end sheet 1, and also 65 riveted to the vertical portions of sheets

1 and 8 and side plate 15. The cap 16 has a top portion which forms a gusset plate for the corner, and firmly bracing it against distortion. The end sill and side sill being connected together at the bottom of the structure by the angle joint member 17, operate to similarly brace the lower end of the corner and tubular corner post. 70

The tubular corner posts, being thus firmly connected and braced at their upper and lower extremities to the framing members of the car, are further braced at their medial portion by the beam member formed by the transverse beads 5, attaching flanges 6, and tie plate 7. 75

In Fig. 6, I have shown a modified arrangement for joining sections 1 and 2, in which a channel member 3 is interposed, being riveted to the attaching flanges 6. This channel member forms a rigid girth 80

across the end structure and connecting the tubular corner posts. The beads 5 in this modified form, are formed similarly to those in the form illustrated in Figs. 1 and 4. It will be noted that the bead is formed broadest and highest at the center or median line of the sections and that it tapers in both width and height toward the corner margins. This is for the purpose of giving the greatest strength on the median line of 90

the sections where cargo thrusts would be likely to do the greatest damage. It will be observed that this variation in width and height is due to the variation in the width of the offset portions 5. When the section 100 is thus flanged outwardly along its margin to form the offset portion 5, the adjacent margin of the section will not be straight, but the section will be widest at its lateral margins and narrowest at its center. When 105

the attaching flanges 6 are formed, however, the meeting margins of the sections are made straight or brought into alignment by increasing the amount of material in the flange from the center to the side margins, the excess width of metal in the lateral portions being turned into the flange. Thus the flanges 6 are narrowest at the middle or median line and gradually increase in width to the lateral margins. Thus where 110 the most material is used in the offset portion 5, the least material is used in the flange 6, and vice versa. Hence, the meeting margins of the sections are made straight without necessitating shearing off any of the 115 material. 120

It will be obvious from the foregoing that my invention provides an exceptionally strong and stable end construction wherein the end and side sheets are so combined as to 125 provide an exceedingly strong connection for the end sheets, and obviate the possibility of breakage of the corner posts by thrusts delivered against the end sheets, and in which the end sheets are combined 130

to form a beam member which operates to prevent their being distorted, and to brace and stay the corner posts.

I am aware that the construction is capable of variations and modifications without departing from the scope of the invention.

What I claim is:

1. In an end structure for cars, a pair of sheet metal sections juxtaposed and having their adjacent marginal portions shaped to provide offset beads and connecting flanges which unite on lines outside the plane of the sections to form a reinforcing member which is broadest and highest at the medial portion of the end structure and which tapers to the lateral margins thereof.
2. In a car end, a pair of sheet metal sections having their meeting edges secured together and displaced to form a bead or corrugation having its greatest transverse width at the medial portion of the end structure and tapering in width to the outer margins thereof.
3. In a car end, a sheet metal section having a marginal portion shaped to form an offset bead and connecting flange, the bead varying in width and height throughout its length for the purpose described.
4. In a car end, a sheet metal section having a portion adjacent a margin thereof displaced to form an offset portion and an attaching flange, said offset portion tapering in width from said margin throughout its length.
5. In a car end structure, the combination of end sheets and side sheets formed and connected together to provide tubular corner posts at their junction, side plates, and gusset plates connecting the side and end sheets and secured to the side plates.
6. In combination with the horizontal framing members of a car, end sheets and side sheets connected to said framing members and shaped and connected together to form tubular vertical framing members cooperating therewith, and gusset plates connecting the side and end sheets across ends of such vertical framing members.
7. In a car end structure, end and side sheets having their marginal portions, overlapped and secured together at the corners of the car to form tubular corner posts, said end sheets having outwardly directed flanges extending around the outside of such corner posts.
8. In a car end structure, end sheets having their lateral margins deflected rearwardly from the plane of the end wall, and side sheets cooperating with said deflected portions to form tubular corner posts, said

end sheets having flanges extending around the outer sides of such corner posts and standing at an angle relative thereto.

9. In combination with horizontal framing members of a car, end sheets and side sheets secured to said framing members and to each other to provide tubular corner posts, said end sheets having horizontal flanges extending intermediate and about 70 the outer sides of such corner posts.

10. In a car, side sheets having their terminal marginal portions bent to form a channel, and end sheets disposed with their marginal portions overlapping the marginal 75 portions of the side sheets and secured thereto to form tubular corner posts, said end sheets having outwardly extending flanges connecting the corner posts.

11. In a car end, a pair of sheet metal 80 sections having their meeting margins secured together and having the portions adjacent said meeting margins displaced to form complementary offset portions widest at the center and tapering toward the sides, 85 and means tying said sections together across the reentrant sides of said offset portions.

12. In a car end, a pair of sheet metal sections having their meeting edges secured together and displaced together with portions adjacent thereto to form a corrugation disposed partially in each section, and tapering in width from its middle to its ends, and a plate secured to said sections at opposite 95 sides of said corrugation and tying said sections together.

13. In a car structure, side sheets and end sheets having their lateral margins shaped and secured together to form corner posts, 100 said end sheets being corrugated and flanged to form a transverse beam member extending from one of said corner posts to the other and merging at its extremities into the metal forming parts thereof to provide 105 a transverse reinforcement connecting said posts.

14. In a car end, a pair of sheet metal sections having their meeting edges conjoined and displaced, together with portions 110 adjacent thereto, to form a corrugation disposed partially in each section, which corrugation tapers in width toward its extremities.

In testimony whereof I hereunto affix my 115 signature in the presence of two witnesses, this eighth day of March, 1915.

PAUL M. BEARD.
